Primary Examiner — Jasmine Mlinarcik(74) *Attorney, Agent, or Firm* — Dunlap Bennett & Ludwig, PLLC; Brendan E. Squire(57) **CLAIM**

The ornamental design for a visor, as shown and described.

DESCRIPTION

FIG. 1 is a top front perspective view of a visor showing my new design;

FIG. 2 is a right side elevation view thereof, with the left elevation view being a mirror image thereof;

FIG. 3 is a front elevation view thereof;

FIG. 4 is a rear elevation view thereof;

FIG. 5 is a top plan view thereof; and,

FIG. 6 is a bottom plan view thereof.

The broken lines shown in the drawings illustrate portions of the visor that form no part of the claimed design.

1 Claim, 4 Drawing Sheets(56)
